METHOD OF AND APPARATUS FOR SORTING
CARDSEdwin G. Harrison, Jr., Nutley, N. J., assignor to
Ditto, Incorporated, Chicago, Ill., a corporation
of West Virginia

Application June 5, 1939, Serial No. 277,340

24 Claims. (Cl. 209—72)

This invention relates to an improved method of sorting cards or other flexible sheets and to improved means for carrying out the method, together with an improved form of card or other piece of sheet material for use in the practice of the method of sorting. The arrangement is such that my improved machine can be operated in connection with a duplicating machine or other source of copy sheets for sorting the sheets and distributing them into a considerable number of trays or other suitable receivers ready for convenient and quick handling.

In the practice of my invention in the preferred manner as disclosed, where the sheets are received from a duplicating machine or other suitable source, the sheets or cards are preliminarily slit at their leading edges before being fed to the duplicating machine, the slits in the several sheets being differentially located transversely of the sheets according to the particular tray or other receiver into which any given sheet is to be directed. Means is provided in the sorting mechanism for spreading the portions of the sheet forwardly and backwardly at opposite sides of the slits against the inherent resiliency of the sheet material, the sheets being presented in such spread condition to a series of fingers arranged in spaced relation to each other transversely of the path of movement of the sheets. The construction is such that the sheet portion directly at the inner end of the slit is caused to pass between two adjacent fingers, after which the spread portions of the sheet are pressed back into substantial alignment with the body of the sheet so as to enable the sheet to pass smoothly and easily along, guided by the fingers which are broadened out transversely into the form of broad plates for leading the sheet to the individual tray for which it is intended. The determination as to which two fingers shall receive the sheet between them is controlled by the location of the slit in the leading edge of the sheet, with the result that all of the sheets having slits similarly located in one position are collected in one tray, all the sheets having slits similarly located in a second position are collected in a second tray, and so on throughout the range of differentially located slits.

In the arrangement illustrated in my drawings, the differentially slitted leading edge portions of the sheets are pressed forwardly at one side of the slit by an arm engaging the sheet near the corresponding side edges of the sheets, the leading edge portion of each sheet at the opposite side of the slit being pressed backwardly

by a second arm engaging said opposite side edge portion of the sheet, such arms in the arrangement shown being moved into and out of operative sheet pressing position in timed relation to the movement of the sheets into the machine. 5 In the arrangement shown, the sheet forwarding means is operated likewise in timed relation to the feeding of the sheets into the machine. In the construction illustrated, the deflected front edge portions of the sheets are brought back into 10 alignment with the bodies of the sheets, after the critical selection point of the movement has been passed, by means of roller brushes which engage the faces of the sheets, the brushes being preferably in the form of wooden rollers each 15 covered by a layer of cloth such as plush having a heavy nap which has sufficient strength for bringing about the desired direction of the edges of the sheets along the prescribed path without being so stiff as to tear or otherwise deface the 20 sheets.

In the arrangement shown, the fingers are aligned accurately with respect to each other transversely of the machine side by side, but they are twisted slightly with respect to the 25 broadened plate extensions so that the plane of each of the fingers is in angular relation to the line of fingers. This enables the fingers to stand in spaced face to face relation to each other at a point a short distance from the ends 30 of the fingers, at which point they are broadened out so as to overlap to a slight degree. The plate portions forming the bottom extensions of the fingers are arranged substantially parallel with each other, being spaced forwardly and 35 backwardly of the machine as distinguished from the upper end portions of the fingers which are in transverse alignment with each other.

My improved method comprises the preliminary step of slitting a plurality of sheets differentially, and then subjecting the sheets to pressure by which the sheet portion at one side of the slit is pressed into angular position with respect to the sheet portion at the opposite side of the slit, so as to enable me to cause the sheets 40 to move through different paths corresponding to the varied positions of the slits in the different sheets, the deflected sheets portions being preferably pressed back into substantially their normal positions in alignment with the body of 45 the sheet as soon as the selection of the path for the sheet has been effected. The sheet is thus caused to pass smoothly and evenly along the path provided by the fingers.

It is another object of my invention to im- 55

prove machines and devices and methods of this type in sundry details hereinafter pointed out. The preferred means by which I have accomplished my several objects are illustrated in the accompanying drawings, in which—

Fig. 1 is an end view of a preferred form of my improved machine;

Fig. 2 is a view of the machine as seen from the right in Fig. 1;

10 Fig. 3 is a vertical sectional view taken upon an enlarged scale at the line 3—3 of Fig. 2;

Fig. 4 is a perspective diagrammatic view showing the arrangement of one of the trays in relation to the adjacent fingers and connected plates;

Fig. 5 is a fragmentary top face view of a small pack of cards or sheets, broken away at one end and spread into overlapping relation to show the differential positioning of the slits in the sheets;

20 Fig. 6 is a diagrammatic view showing the connection between two operating shafts for causing them to rotate together;

Fig. 7 is a vertical sectional view taken substantially at the line 7—7 of Fig. 1;

25 Fig. 8 is an end view of a fragmentary portion of the machine as seen from the right in Fig. 2;

Fig. 9 is a vertical sectional view taken substantially at the line 9—9 of Fig. 3;

30 Fig. 10 is a view similar to a portion of Fig. 9 but showing a sheet in changed position in its movement through the machine;

Fig. 11 is a perspective diagrammatic view showing a plurality of fingers with a sheet in its spread condition at about the start of the movement of the sheet between two of the fingers;

35 Fig. 12 is a view similar to Fig. 11 but showing the sheet in a slightly farther advanced position;

40 Fig. 13 is a horizontal sectional view taken at the line 13—13 of Fig. 11;

Figs. 14 and 15 are horizontal sectional views taken respectively at the line 14—14 and the line 15—15 of Fig. 12;

45 Fig. 16 is a perspective diagrammatic view showing a sheet being spread at its leading edge portion for effective engagement with the fingers for enabling them to make the desired selection of the path which the sheet shall follow;

50 Fig. 17 is a diagrammatic view showing the condition of the parts when the sheet has advanced very slightly beyond the position illustrated in Fig. 16;

Fig. 18 is a horizontal sectional view taken substantially at the line 18—18 of Fig. 20, showing the relation of the parts before the leading edge portions of the sheet are spread in opposite directions;

55 Fig. 19 is a view similar to Fig. 18 but showing the spreading arms active with relation to the sheet and also showing the guiding fingers in addition to the parts illustrated in Fig. 18, the showing being substantially a section at the line 19—19 of Fig. 21;

60 Fig. 20 is a vertical sectional view taken substantially at the line 20—20 of Fig. 18; and

Fig. 21 is a vertical sectional view taken substantially at the line 21—21 of Fig. 19.

Referring now to the several figures of the drawings, in which corresponding parts are indicated by the same reference characters, 25 indicates a framework comprising at each end of the machine a plurality of upright frame bars 26, 27, 28 and 29 which in the arrangement shown 75 are connected rigidly together by means of cross

bars 30. In the arrangement shown, the bars at opposite ends of the machine are rigidly connected together by means of brace rods 31, as is best shown in Fig. 2.

Upon the framework above described, I have 5 removably mounted a series of trays 32, such trays being obliquely disposed, with part of the trays extending toward the front, and part of them extending toward the rear, as is clearly shown in Fig. 1. Each of the trays is removably 10 mounted in position by means of flat arms 33 extending from the ends of the trays (see Fig. 2) into position to engage obliquely disposed notches in the upright frame bars of the machine.

At their upper ends, the frame bars 27 and 28 15 are provided with end plates 34, with brace rods 35 connecting the plates for giving the framework the required rigidity (see Fig. 2). The upper ends of the end plates 34 are also rigidly connected together by means of a transversely positioned plate 36 standing in substantially vertical position, as is best shown in Fig. 3, with reinforcing flanges 37 at opposite ends of the machine. In front of the plate 36, (at the left in Fig. 1) I have provided a table 38 adapted to receive a pile 25 of cards or other pieces of sheet material thereon. As is best shown in Fig. 3, the rear edge portion of the table 38 is turned downwardly in the form of a flange 39 in forwardly spaced relation to the plate 36 so as to enable an operator to 30 insert a sheet between the table and the plate 36.

Between the flanges 37 of the plate 36, I have mounted a bar 40 upon which I have mounted brackets 41 which are slidable longitudinally of 35 the machine. As is best shown in Fig. 3, the brackets 41 extend toward the front over the plate 36, being provided at their forward end portions with margin bars 42 which in adjusted position along the plate 36 determine the point at 40 which sheets are to be fed into the machine.

Below the table 38 and the vertically disposed plate 36, I have rotatably mounted a roller 43 having a metal surface and a roller 44 having a sponge rubber facing, such rollers being in co-operative relation to each other, as is clearly 45 shown in said Fig. 3. Above the rollers 43 and 44, I have provided guide plates 45 and 46 which are in position to guide a sheet of paper moving downwardly on the face of the plate 36 so as to direct such sheet to the rollers 43 and 44. The plates 45 and 46 are provided with downwardly extending fingers 47 extending in close proximity to the rollers 43 and 44.

Immediately below the rollers 43 and 44, I 55 have provided a series of upwardly extending fingers 48, the upper end portions of which are in accurately aligned position with respect to each other transversely of the machine, as is best shown in Fig. 13. The fingers 48 are broadened 60 out slightly at a fairly short distance from their upper ends so as to cause the fingers to stand in overlapping relation, as is clearly shown in Figs. 11 and 15, for example, the fingers at their overlapping portions being in spaced face to 65 face relation, as is best shown in Fig. 15. At still lower points, the fingers 48 are provided with downward extensions in the form of broad plates 49, the plates 49 being also in spaced face to face relation to each other. For enabling the 70 upper end portions of the fingers 48 to stand in exact alignment side by side with respect to each other, while the plate portions 49 extend directly across longitudinally of the machine, the fingers are twisted slightly, as is best indicated in Figs. 13 75

and 14. As is best shown in Fig. 3, the lower ends of the plates 49 lead to trays 32, some of such plates 49 being bent forwardly and some of them being bent backwardly, as shown in said Fig. 3, 5 for securing the desired result.

For enabling a bunch of sheets to be sorted in my machine, I provide each of the sheets with a slit 50 in its edge as indicated in Fig. 5, the several sheets as illustrated in said figure being indicated by the numeral 51. The sheets 51 are slotted differentially with respect to each other, the spacing between the different positions of the slits as illustrated in Fig. 5 corresponding with the transverse spacing of the fingers 48 of the 10 machine. The arrangement is such that when a sheet 51 is fed downwardly between the table 38 and the plate 36 the slit 50 in the leading edge of the sheet will be positioned transversely of the machine at a point substantially midway between the end portions of two adjacent fingers 48. For 15 accomplishing this purpose, it is necessary that the margin plates 42 be positioned accurately longitudinally of the rod 40 upon which the carrying brackets 41 are mounted.

20 In my improved machine, means is provided for spreading the leading edge portions of the sheet with respect to each other as the sheets approach the line of fingers 48. In the arrangement shown, the portion of the sheet at one side of the slit is 25 pressed forwardly and the portion at the opposite side is pressed backwardly. This is accomplished in the arrangement shown by two arms 52 and 53 (see Fig. 3) which are mounted upon brackets 54 carried by shafts 55 and 56 rotatably mounted 30 between the end plates 34 of the machine. At the near end of the machine as shown in Fig. 1, the shafts 55 and 56 are provided with arms 57 and 58 respectively fixedly mounted in position, the outer ends of said arms being pivotally connected together by means of a link 59, the arrangement being such that upon rotary movement of one of the shafts in one direction the other shaft is given a rotary movement in the opposite direction. At the opposite end of the 35 machine (see Fig. 8), the shaft 55 is provided with an arm 60 fixedly mounted thereon, such arm being provided with a link extension 61 which in turn is provided with an actuating member 62 extending into the path of a pin 63 carried 40 by a gear 64 fixedly mounted upon a shaft 65 extending lengthwise of the machine with a crank handle 66 on its outwardly extending end portion for rotating the shaft. The arrangement is such that at one point in the rotation of the 45 gear 64 the pin 63 by engagement with the operating member 62 rotates the shaft 55 in counterclockwise direction in Fig. 8 (in clockwise direction in Fig. 3) for swinging the arm 52 toward the left into position beneath the roller 44. The 50 arrangement of the link 59 and its cooperating parts at the opposite end of the machine at the same time causes the arm 53 to swing in counterclockwise direction in Fig. 3 so as to extend underneath the roller 43. The shaft 55 in the 55 construction illustrated is provided with a coiled spring 67 normally holding the shaft 55 in the position as shown in Fig. 3.

Below the rollers 43 and 44 at opposite sides of the row of fingers 48, I have mounted a pair of 60 rollers 68 and 69, each of which in the construction illustrated comprises a bar of wood covered by a facing of plush. The roller 69 is mounted upon a fixed axis between the plates 34, while the roller 68 is rotatably mounted between two 65 pivotally mounted arms 70 which are pressed by 70

coiled springs 71 toward the right in Fig. 8 for causing the rollers 68 and 69 to have cooperative relation to each other. In the arrangement shown, the roller 69 is provided with a pinion 72 which meshes with an idler pinion 73 which in 5 turn is driven by the gear 64 so as to cause the roller 69 to rotate in clockwise direction in Fig. 3 when the gear 64 is driven in counterclockwise direction in Fig. 8. In the construction illustrated, the sponge rubber roller 44 also is provided with a pinion 74 which meshes with an idler pinion 75 which also is driven by the gear 64. The metal roller 43 is driven by friction from the roller 44. The plush covered roller 68 is driven by friction from the roller 69 by means of 10 a driving member 76 of rubber on the roller 69 engaging a reduced portion 77 of the roller 68, as is clearly shown in Fig. 16.

Means is provided in connection with the gear 64 for stopping the gear at the end of each complete revolution. This means in the arrangement shown (see Fig. 8), comprises a block 78 adjustably mounted upon the gear 64 adapted to be brought into engagement with a pin 79 removably mounted in the table 38 when the gear 20 reaches the position as shown in said figure. When the rotation of the shaft 65 is to be renewed, the pin 79 is drawn upwardly by the operator through the instrumentality of a head 80 on the pin so as to permit the block 78 to pass 25 readily to be engaged at the end of another complete revolution.

With the parts in the arrangement as shown in Fig. 3, and with the forward rotation of the gear 64 limited by the engagement of the block 35 78 with the pin 79 as shown in Fig. 8, a sheet 51 is inserted by the operator between the table 38 and the plate 36, being positioned lengthwise of the machine by the margin bars 42 as above described. As soon as the sheet has been brought 40 to rest by engagement with the rollers 43 and 44, the operator withdraws the pin 79 and rotates the shaft 65 in counterclockwise direction in Fig. 8, or clockwise direction in Fig. 1, so as to draw the sheet 51 downwardly between the rollers 43 and 45 44. The arrangement of the parts is such that as the sheet 51 begins to move downwardly the arms 52 and 53 are swung through the action of the pin 63 and its cooperating parts into engagement with the front edge portions of the sheet 50 55 51 so as to press the portion at one side of the slit 50 forwardly through the action of the arm 52 and to press the portion of the sheet at the opposite side of the slit backwardly through the action of the arm 53 so as to spread such portions 55 into substantially the position as shown in Figs. 16, 17 and 19. This action carries one portion of the leading edge of the sheet on one side of the line of fingers 48, as shown in Figs. 13 and 17, and carries the other portion of the sheet into 60 position at the opposite side of the line of fingers. As the sheet continues its downward movement as shown in Fig. 11, the body of the sheet beyond the inner end of the slit 50 is carried into the space between two adjacent fingers 48. As will be 65 readily understood, the determination as to which of the spaces between successive fingers is occupied by the body of the sheet is controlled by the position of the slit 50 transversely of the sheet. That is to say, when the sheets 51 as 70 shown in Fig. 5 with the slits 50 differentially positioned transversely of the sheets, are fed into the machine, each successive sheet is fed into a different one of the spaces between successive fingers, since each successive sheet in the pack as 75

illustrated in Fig. 5 is slotted at a different point from that at which the adjacent sheet is slotted.

After the sheet has progressed to the point as shown in Fig. 11, with the body of the sheet 5 definitely in position in a selected one of the spaces between the fingers 48, the deflected forward edge portions of the sheet must be pressed back substantially into alignment again with the body of the sheet so as to enable the sheet to pass 10 smoothly and easily between the fingers and later between the plates 49 for delivery to the selected one of the trays 32. This result is effected by a brushing effect upon the sheets for forcing them 15 into the bite of the rollers for insuring easy forward movement of the sheets along the selected pathways.

In the preferred embodiment of my improved machine, the sheets 51 are to be fed to the rollers 20 43 and 44 as they come from a duplicating machine or other suitable source. In such case, the sorting mechanism is to be operated in timed relation to the delivery of the sheets by the duplicating machine, so as to make it unnecessary for 25 an operator to release the pin 79 upon successive rotations of the shaft 65.

I have found by the use of my improved machine that it is very effective for sorting sheets into a selected number of piles or packs in accordance with a differential slitting of the corresponding edge portions of the sheets. I have found that the machine can be operated rapidly and effectively by ordinarily skilled operators with no special training with respect to such operation.

33 It is to be understood that the drawings are to be taken merely as illustrative of one form of the invention and that the invention is not to be limited to the arrangement shown except as the claims may be so limited, it being understood 40 that changes might well be made in the arrangement and form of the parts without departing from my invention.

I claim:

1. The method of sorting pieces of sheet material having slits differentially arranged in their edges, comprising pressing the portions of the sheets at one side of said slits into changed angular position with respect to the portions at the opposite side of the slits, and then directing the sheets along different paths of movement corresponding to the varied positions of said slits.

2. The method of sorting pieces of sheet material, which comprises the preliminary step of slitting the sheets at corresponding edges, then pressing the portions of the sheets at one side of said slits into changed angular position with respect to the portions at the opposite side of the slits, and then directing the sheets along different paths of movement corresponding to the varied positions of said slits.

3. The method of sorting pieces of sheet material having slits differentially arranged in their edges, comprising pressing the side portions of the sheets in opposite directions at opposite sides of said slits, and then directing the sheets along different paths of movement corresponding to the varied positions of said slits.

4. The method of sorting pieces of sheet material having slits differentially arranged in their edges, which comprises feeding said sheets forwardly along a common path, pressing the portions of the sheets at one side of said slits into changed angular position with respect to the portions at the opposite side of the slits, and then as the sheets 75 pass on diverting the sheets from said common

path to a plurality of different paths with all similarly slotted sheets passing along the same path.

5. The method of sorting pieces of sheet material having slits differentially arranged in their edges, which comprises feeding said sheets forwardly along a common path, pressing the portions of the sheets at one side of said slits into changed angular position with respect to the portions at the opposite side of the slits, and presenting said sheets with differentially angled portions to a series of spaced fingers which have differential engagement with the sheets depending on the varied positions of the slits so as to direct the sheets along different paths with all similarly 15 slotted sheets passing along the same path.

6. The method of sorting pieces of sheet material having slits differentially arranged in their edges, which comprises feeding said sheets forwardly along a common path, pressing the portions of the sheets at one side of said slits into changed angular position with respect to the portions at the opposite side of the slits, presenting said sheets having differentially angled portions to a series of spaced fingers which have differential engagement with the sheets depending on the varied positions of the slits, and then pressing said angled portions of the sheets back substantially into their initial aligned position with respect to the body of the sheet for causing the 30 sheets to pass smoothly between the fingers so as to be directed along different paths of movement.

7. An apparatus for sorting pieces of sheet material having slits differentially arranged in their edges, comprising in combination means for directing such slitted sheets into the apparatus, means adapted by engagement with a sheet in its movement into the machine to spread the portions at opposite sides of the slit by angling the 40 portion at one side of the slit with respect to the portion at the opposite side, and means adapted by differential engagement with said differently slitted sheets to direct the sheets along different paths of movement.

8. An apparatus for sorting pieces of sheet material having slits differentially arranged in their edges, comprising in combination means for directing such slitted sheets into the apparatus with the slitted edges of the sheets in the lead, means 50 adapted by engagement with a sheet in its movement into the machine to angle the portion forwardly at one side of the slit and to angle the portion backwardly at the opposite side of the slit, and means adapted by differential engagement 55 with the angled portions of the differently slitted sheets to direct them along different paths of movement.

9. An apparatus for sorting pieces of sheet material having slits differentially arranged in their edges, comprising in combination means for directing such slitted sheets into the apparatus, means adapted by engagement with a sheet in its movement into the machine to spread the portions at opposite sides of the slit by angling the 65 portion at one side of the slit with respect to the portion at the opposite side, and a plurality of fingers in spaced relation to each other transversely of the apparatus adapted by differential engagement therewith to direct the differently 70 slitted sheets into different spaces between adjacent fingers.

10. An apparatus for sorting pieces of sheet material having slits differentially arranged in their edges, comprising in combination means for 75

directing such slitted sheets into the apparatus, means adapted by engagement with a sheet in its movement into the machine to spread the portions at opposite sides of the slit by angling the 5 portion at one side of the slit with respect to the portion at the opposite side, a plurality of fingers in spaced relation to each other transversely of the apparatus adapted by differential engagement with the differently slitted sheets to direct 10 such sheets into different spaces between adjacent fingers, and extensions of said fingers in the form of broad plates in spaced relation to each other for collecting the sheets at separate points.

11. An apparatus for sorting pieces of sheet 15 material having slits differentially arranged in their edges, comprising in combination means for directing such slitted sheets into the apparatus, means adapted by engagement with a sheet in its movement into the machine to spread the portions 20 at opposite sides of the slit by angling the portion at one side of the slit with respect to the portion at the opposite side, and a plurality of fingers in spaced relation to each other transversely of the apparatus at their outer end portions 25 and broadened somewhat at their inner end portions so as to overlap with respect to each other in slightly spaced face to face relation to each other and adapted by differential engagement with the differently slitted sheets to direct 30 such sheets into different spaces between adjacent fingers.

12. An apparatus for sorting pieces of sheet material having slits differentially arranged in their edges, comprising in combination means for 35 directing such slitted sheets into the apparatus, means adapted by engagement with a sheet in its movement into the machine to spread the portions at opposite sides of the slit by angling the portion at one side of the slit with respect to the portion 40 at the opposite side, a plurality of fingers in spaced relation to each other transversely of the apparatus at their outer end portions and broadened somewhat at their inner end portions so as to overlap with respect to each other in slightly 45 spaced face to face relation and adapted by differential engagement with the differently slitted sheets to direct such sheets into different spaces between adjacent fingers, and extensions of said fingers in the form of broad plates in spaced relation 50 to each other and in angular position with respect to said fingers for collecting the sheets at separate points.

13. An apparatus for sorting pieces of sheet material having slits differentially arranged in 55 their edges, comprising in combination means for directing such slitted sheets into the apparatus, means adapted by engagement with a sheet in its movement into the machine to spread the portions at opposite sides of the slit by angling the 60 portion at one side of the slit with respect to the portion at the opposite side, a plurality of fingers in spaced relation to each other transversely of the apparatus adapted by differential engagement with the differently slitted sheets to direct such 65 sheets into different spaces between adjacent fingers, extensions of said fingers in the form of broad plates in spaced relation to each other with some of said plates deflected forwardly and some deflected backwardly for maintaining the desired 70 spaced relation, and trays in operative receiving position below said plates for collecting the sheets at separate points.

14. An apparatus for sorting pieces of sheet material having slits differentially arranged in 75 their edges, comprising in combination means

for directing such slitted sheets into the apparatus, means adapted by engagement with a sheet in its movement into the machine to spread the portions at opposite sides of the slit by angling the portion at one side of the slit with 5 respect to the portion at the opposite side, a plurality of fingers in spaced relation to each other transversely of the apparatus adapted by differential engagement with the differently slitted sheets to direct such sheets into different spaces 10 between adjacent fingers, and means adapted by engagement with the sheet near the free ends of the fingers to press the spread side portions of the sheet back into substantially the plane of the body of the sheet for causing the sheets to 15 pass smoothly along their paths between the fingers.

15. An apparatus for sorting pieces of sheet material having slits differentially arranged in their edges, comprising in combination means 20 for directing such slitted sheets into the apparatus, means adapted by engagement with a sheet in its movement into the machine to spread the portions at opposite sides of the slit by angling the portion at one side of the slit with 25 respect to the portion at the opposite side, a plurality of fingers in spaced relation to each other transversely of the apparatus adapted by differential engagement with the differently slitted sheets to direct such sheets into different spaces 30 between adjacent fingers, and driven rotary members adapted by engagement with the sheet near the free ends of the fingers to press the spread side portions of the sheet back into substantially the plane of the body of the sheet for 35 causing the sheets to pass smoothly along their paths between the fingers.

16. An apparatus for sorting pieces of sheet material having slits differentially arranged in their edges, comprising in combination means 40 for directing such slitted sheets into the apparatus, means adapted by engagement with a sheet in its movement into the machine to spread the portions at opposite sides of the slit by angling the portion at one side of the slit with 45 respect to the portion at the opposite side, a plurality of fingers in spaced relation to each other transversely of the apparatus adapted by differential engagement with the differently slitted sheets to direct such sheets into different spaces 50 between adjacent fingers, and driven rollers in the form of brushes adapted by engagement with the sheet near the free ends of the fingers to press the spread side portions of the sheet back into substantially the plane of the body of the sheet for 55 causing the sheets to pass smoothly along their paths between the fingers.

17. An apparatus for sorting pieces of sheet material having slits differentially arranged in their edges, comprising in combination means 60 for directing such slitted sheets into the apparatus, means adapted by engagement with a sheet in its movement into the machine to spread the portions at opposite sides of the slit by angling the portion at one side of the slit with 65 respect to the portion at the opposite side, a plurality of fingers in spaced relation to each other transversely of the apparatus adapted by differential engagement with the differently slitted sheets to direct such sheets into different spaces 70 between adjacent fingers, and driven rollers comprising face portions of plush adapted by the engagement of the nap with the paper between the fingers near the free ends of the fingers to press the spread side portions of the sheet back 75

into substantially the plane of the body of the sheet for causing the sheets to pass smoothly along their paths between the fingers.

18. An apparatus for sorting pieces of sheet material having slits differentially arranged in their edges, comprising in combination means for directing such slitted sheets into the apparatus, means adapted by engagement with a sheet in its movement into the machine to spread the portions at opposite sides of the slit by angling the portion at one side of the slit with respect to the portion at the opposite side, a plurality of fingers in spaced relation to each other transversely of the apparatus adapted by differential engagement with the differently slitted sheets to direct such sheets into different spaces between adjacent fingers, and driven rollers in slightly spaced relation to said fingers adapted by engagement with a sheet to present the sheet to said fingers and to cause the sheets to advance along the fingers for delivery.

19. An apparatus for sorting pieces of sheet material having slits differentially arranged in their edges, comprising in combination means for directing such slitted sheets into the apparatus, means adapted by engagement with a sheet in its movement into the machine to spread the portions at opposite sides of the slit by angling the portion at one side of the slit with respect to the portion at the opposite side, a plurality of fingers in spaced relation to each other transversely of the apparatus adapted by differential engagement with the differently slitted sheets to direct such sheets into different spaces between adjacent fingers, and driven rollers in slightly spaced relation to said fingers comprising a metal roller and a sponge rubber roller adapted by engagement with the sheet to present the sheet to said fingers and to cause the sheets to advance along the fingers for delivery.

20. An apparatus for sorting pieces of sheet material having slits differentially arranged in their edges, comprising in combination means for directing such slitted sheets into the apparatus, means adapted by engagement with a sheet in its movement into the machine to spread the portions at opposite sides of the slit by angling the portion at one side of the slit with respect to the portion at the opposite side, a plurality of fingers in spaced relation to each other transversely of the apparatus adapted by differential engagement with the differently slitted sheets to direct such sheets into different spaces between adjacent fingers, a pair of driven rollers in slightly spaced relation to said fingers adapted by engagement with a sheet to present the sheet to said fingers and to cause the sheets to advance along the fingers, and a second pair of driven rollers in the form of brushes adapted by engagement with the sheet between the fingers near the free ends of the fingers to press the spread side portions of the sheet back into substantially the plane of the body of the sheet for causing the sheets to pass smoothly along their paths between the fingers.

21. An apparatus for sorting pieces of sheet material having slits differentially arranged in their edges, comprising in combination means for directing such slitted sheets into the apparatus, means adapted by engagement with a sheet in its movement into the machine to spread the portions at opposite sides of the slit by angling the portion at one side of the slit with respect to the portion at the opposite side, a plu-

rality of fingers in spaced relation to each other transversely of the apparatus adapted by differential engagement with the differently slitted sheets to direct such sheets into different spaces between adjacent fingers, rollers in the path of movement of a sheet into said machine adapted when stationary to stop a sheet in slightly spaced relation to said fingers and adapted when driven to present the sheet to said fingers and to cause the sheet to advance along the fingers for delivery, means for driving said rollers, and releasable means for stopping the rotation of said rollers at intervals.

22. An apparatus for sorting pieces of sheet material having slits differentially arranged in their edges, comprising in combination means for directing such slitted sheets into the apparatus, a plurality of fingers in spaced relation to each other transversely of the apparatus and arranged in the path of movement of said sheets, means adapted when in operation to forward sheets to said fingers, means for driving said forwarding means, and means acting in timed relation to the operation of said forwarding means for pressing the portion of said sheet at one side of said slit into angular relation to the portion at the opposite side of the slit for causing said fingers to have differential engagement with the differently slitted sheets for directing the sheets into different spaces between said fingers.

23. An apparatus for sorting pieces of sheet material having slits differentially arranged in their edges, comprising in combination means for directing such slitted sheets into the apparatus, a plurality of fingers in spaced relation to each other transversely of the apparatus and arranged in the path of movement of said sheets, means adapted when in operation to forward sheets to said fingers, means for driving said forwarding means, and means acting in timed relation to the operation of said forwarding means for pressing forwardly the portion of said sheet at one side of said slit and for pressing backwardly the portion of the sheet at the opposite side of said slit so as to cause said fingers to have differential engagement with the differently slitted sheets for directing the sheets into different spaces between adjacent fingers.

24. An apparatus for sorting pieces of sheet material having slits differentially arranged in their edges, comprising in combination means for directing such slitted sheets into the apparatus, a plurality of fingers in spaced relation to each other transversely of the apparatus and arranged in the path of movement of said sheets, a pair of rollers in slightly spaced relation to said fingers adapted when stationary to stop a sheet adjacent to said fingers and adapted when driven to forward the sheet to said fingers and to cause the sheet to advance along the fingers, means for driving said rollers, releasable means for stopping the rotation of said rollers at intervals, and means acting in timed relation to the operation of said rollers for pressing the portion of the sheet at one side of the slit into angular position with respect to the portion of the sheet at the opposite side of the slit at about the time when the sheet reaches said fingers so as to cause said fingers to have differential engagement with the differently slitted sheets for directing the sheets into different spaces between adjacent fingers.
